Specification of Letters Patent.

Patented Dec. 14, 1920.

Application filed April 29, 1918. Serial No. 231,340.

To all whom it may concern:

Be it known that I, EDWIN J. PRINDLE, a citizen of the United States, residing at East Orange, in the county of Essex and State of New Jersey, have invented certain Improvements in the Manufacture of Articles Having a Systematic Resemblance to a Pattern, of which the following description, in connection with the accompanying drawings, is a specification, like reference characters on the drawings indicating like parts in the several figures.

This invention relates to pattern copying, or the production of objects having a systematic resemblance to a pattern used as a guide or templet, and is disclosed as embodied in a last lathe. Many of the principles and features of the invention are of broad application to the entire class of pattern copying machinery including the production of objects having less than three dimensions, such, for example, as patterns for soles, shoe uppers, clothing, etc., and accordingly I do not intend that all of the appended claims shall be limited in scope to pattern reproducing machinery of the last making or even of the three-dimensional type, and I have therefore in many of the claims, used words and terms in a generic sense as applying to the broad class of machinery of the pattern reproducing type.

It is well known that the width grading mechanism used on last lathes has been unsatisfactory in very important respects. It is substantially pantographic in its action, multiplying all perpendicular distances from the grading axis which in these machines is the axis of rotation of the model to its surface by a factor constant throughout the turning. The model is suspended on centers engaging its heel and toe tip, and in cutting lasts wider than the model the toe spring, which is the vertical distance between the bottom of the ball and the toe tip, is increased progressively as the last being cut becomes wider.

For instance, the 4B model is $7\frac{1}{2}$ inches in perimeter at the ball. The 4EE last is $8\frac{1}{2}$ inches in perimeter, and therefore about $\frac{1}{4}$ inch greater in thickness, at this point. The differences between the 4EE and the 4B may perhaps be most easily seen by regarding the latter as hung inside the former, upon homologous axes (which will be pref-

erably their axes of rotation in the lathe) 55 and by considering the material which is added to the 4B by the width grader to make the 4EE. This material is added by multiplying each radius of the 4B, taken perpendicular to the axis of rotation, by a 60 constant in order to get the corresponding radius of the 4EE. Since the axis of rotation passes through the ball portion near the top of the last, the greater part of this $\frac{1}{2}$ inch is added on the bottom. The axis of 65 rotation passes through the toe, which is therefore reproduced *in situ*. The bottom of the heel, being closer to the axis than the ball, is not "dropped" as far as the bottom of the ball. The result of keeping one end 70 of the bottom profile fixed and moving an internal point of it more than the other end is the creation of a general increase in the curvature of the bottom profile taken as a whole. Since the bottom of the ball rests 75 on the ground, this is especially visible in the forepart, giving rise as stated to an exaggerated "toe spring" or distance from the floor line to the toe tip. The difficulty, 80 though generally spoken of in these terms is, however, fundamentally one of the entire "tread," and the difficulty in the instep is perhaps even more important anatomically than that in the toe. The reverse difficulty occurs in the case of lasts narrower than 85 the model.

Such variations in lasts do not correspond to any natural variations in the feet they are intended to fit, since the toes of wide feet do not "turn up" in correspondence 90 with the increasing toe spring of wide lasts, and vice versa. This difficulty has heretofore been dealt with in two ways. One practice has been to increase the heights of the heels of the wide shoes, in order to 95 diminish the toe spring. This simply treats a symptom and does not reach the root of the difficulty, since the faulty bottom profile remains unchanged, and the shoe not having the design requisite for a high heel, is nevertheless tipped up on one. 100

Another practice adopted by makers of lasts for use in the best shoes, has been to use a number of models in turning the set of lasts. Some last makers make by hand 105 three models in every width and use the width grader only (for instance) in grading the 3B, 4B and 5B lasts from the 4B model.

The 6B, 7B and 8B lasts will be cut from a 7B model; the 3C, 4C and 5C lasts will be cut from a 4C model, and so on. This practice is obviously expensive, and the need 5 of a method or procedure which will produce a series of graded lasts conforming suitably to the feet they are to fit, and more specifically, of a machine which will produce them from a single model which may 10 be called a "universal" machine has long been recognized.

My invention in this specific aspect is directed to the control of the profiles of graded lasts, and to that end I contemplate the production 15 in a block of pantographic reproductions of sections of a model relatively (and more specifically stated, differentially) shifted upon one another in any desired manner. An important feature of the invention, considered from the machine aspect, is accordingly a pattern copying machine having means for producing, in the work, relatively displaced systematic reproductions of sections or differential elements 20 of the model. The meaning of the preceding broad statements relative to my improvements may be better understood from the following specific illustration of the application 25 of my invention to the solution of the special problem stated above. It is obvious that if a wide last of ordinary shape should be produced from a model, and if its forepart should then be sawed into thin laminae preferably perpendicular to its long 30 axis, and if these laminae in the ball and instep portions were then systematically relatively displaced so as to lift them by progressively diminishing amounts proceeding each way from the ball, a last would be 35 formed having the same lateral cross-section at every point and hence having the same "width," but having its longitudinal vertical profile flatter on the bottom than before. Such a last, while giving the desired foot- 40 room, would not entail in the shoe the objectionable drop at the ball which has been described.

While it is of advantage merely to displace relatively such laminae, and indeed, a 45 distinct advantage results even from treating the difficulty as a matter of toe spring alone, and relatively displacing only laminae in front of the ball, a completely successful solution of such a problem must consider the entire tread profile of the last, and must deal 50 individually with each point in it.

My invention therefore contemplates broadly the production in the work of pantographically or otherwise reproduced sections 55 of a model relatively displaced preferably in any arbitrary desired manner. This may be more specifically stated as the production of pantographic reproductions of model sections shifted or displaced upon one another in order preferably at an arbitrarily

variable rate or by amounts arbitrarily predetermined at all points throughout the series of reproductions so shifted.

Considered in another aspect the invention contemplates the relative shifting of 70 the model and work or the shifting of one of them alone relatively transversely to a grading axis with respect to which a grading mechanism is arranged to magnify or reduce differential elements of the model. These 75 differential elements are, for example, sections, strips or laminae of the model which can be regarded as being pantographically reproduced by the grading mechanism. In the machine aspect of the invention, an important 80 feature is comprised in means for the effecting of such relative shifting of model work and grading axis. In the illustrated machine, which is for the reproduction of solid objects, the model is shifted 85 upon the grading axis, which is here the axis of revolution, by a cam arranged in relation to that axis, to produce the desired shift when the lamina related to any particular point of the axis is reached by the reproducing mechanism. 90

Considering the invention from the stand-point of apparatus by means of which its novel methods may be performed in the production of solid objects, I contemplate 95 broadly the presentation of a model and a block to the model wheel and cutter respectively of a last lathe, and the effecting of a change, preferably at an arbitrarily variable rate, in the rotational relations of these four 100 objects during the cutting of a last. In the machine shown in the drawings, by means of which the invention may be practised and which physically embodies an important part of the invention, means is provided for 105 moving the model relatively to its axis of rotation during the turning.

Thus sections of the model to be reproduced are shifted absolutely and relatively out of their normal positions in an arbitrarily variable manner, from point to point, and are therefore reproduced in the block in like absolutely and relatively shifted position, by the machine shown, as will be more fully explained. 110

These and other features of the invention will be further apparent from the following description of its practice by means of a preferred machine embodying the machine aspect of it, it being understood that the 120 scope of the appended claims is not to be determined by the structure or function of the machine shown in the drawings, this being merely one of a number of possible machines by which my invention may be practised, selected for purposes of illustration. 125

In the accompanying drawings,

Figure 1 is a partial front elevation of a last turning lathe, having an embodiment of my invention applied thereto;

Fig. 2 is a side elevation of Fig. 1;

Fig. 3 is a detail sectional view through the head stock spindle, the dog and adjacent parts;

5 Fig. 4 is a plan view of the front end of the head stock spindle and the dog;

Fig. 5 is a plan view of the model carriage and parts for actuating the parts which shift the dog;

10 Fig. 6 is a plan view of another form of cam bar, and

Fig. 7 is a diagrammatic illustration of the type of result accomplished by the invention.

15 I have shown my invention applied to the ordinary Blanchard or last turning lathe, but it is capable of being applied to any lathe for turning lasts. I have illustrated only so much of such a lathe as is necessary 20 to understand my invention.

The model wheel carriage 1 travels along the bed 2 upon a guide 3. The model wheel 1^a, as usual is mounted upon the carriage. The grading mechanisms are of ordinary

25 construction. Brackets 4 rise from the bed and support the pivots 5, from which the ordinary "swing frame" 5' hangs and upon which it swings. The model 6 is supported upon a head stock dog 7 and a dead center 8.

30 The head stock spindle 9 is, as usual, mounted in bearings in the swing frame and is rotated by a spur gear 10, engaged by a pinion 11. The head stock spindle carries a member 12 having a slide 13 dove-tailed 35 into it, so that the slide may move up and down in the member. The slide carries a screw stud 14 upon which is screwed the usual head stock dog 7 which is adapted to engage the heel end of the model.

40 Within the head 12 is a cavity 15 having a bell crank lever 16 mounted upon a fulcrum 17 and having a link 18 connecting the horizontal arm of the bell crank lever with the slide 13. The slide 13 sufficiently overlaps

45 the edges of the cavity, so that it always covers the opening into the cavity in every position and thus prevents chips or sawdust from getting into the cavity. The vertical arm of the bell crank lever is pivoted

50 to a rod 20, passing through a bore or hole through the center of the head stock spindle, which bore is larger than the rod to permit freedom of movement, but is closed by a plug 21 at its rear end that both excludes

55 the dust and forms a bearing for the rod. At its rear end the rod 20 is swiveled to the vertical arm 22 of a bell crank lever. In the form shown the swivel consists of a sleeve 23 on the rod which has a groove 24

60 that is engaged by pins 25, carried by a yoke at the lower end of the said vertical arm and bell crank lever.

The bell crank lever is fulcrumed to a bracket 26 fastened to the swing frame.

65 The horizontal arm 27 of the bell crank le-

ver is pivoted to a vertical rod 28, which extends along the upright of the swing frame to the level of the pivot 5 and is there pivoted to the front arm 29 of a lever which is fulcrumed at 30 upon a bracket secured to 70 the upright 4. The rear arm 31 of the said lever is pivoted to a vertical rod 32, which at its lower end is pivoted to the horizontal arm 33 of a bell crank fulcrumed on the upright 4 and whose vertical arm 34 is pivoted 75 to a bar 35 that extends horizontally forward through a bearing in the bracket 36 on the frame. The said bar carries two pins 37 which straddle a cam rib 38 formed on a slide 39 that is dove-tailed into the carriage 80 1 parallel to the line of movement of the carriage. The slide 39 can be fastened at any desired point by a thumb screw 40.

I have so constructed the parts that the pivot between the arm 29 and the rod 28 is 85 substantially co-axial with the pivot 5 of the swing frame, so that the motion of the swing frame will not cause perceptible movement of the dog 7.

In practising my invention it will be generally preferable, broadly speaking, to raise the ball portions of a wide last being cut by amounts gradually diminishing toward the toe and the rear part of the instep. This means that the corresponding sections of the 95 model must be "raised" in the same way while the cutting is being done in the machine shown. This will be accomplished by raising the heel while the cutting proceeds from the toe to the ball, and lowering it 100 while the cutting proceeds from the ball toward the rear of the instep, so that it reaches normal position, or substantially so, before the heel is reached. The heel and perhaps a rear portion of the instep will be 105 cut substantially according to the old practice. This may be accomplished by properly shaping the cam 38. An illustrative case will be discussed.

Suppose it is desired to cut a last having 110 its lateral dimensions 1.1 times those of the model, and having the same sole profile. In Fig. 7 the full line 43, 44 represents the model. In order to determine the position in the lathe of the bottom profile of the last 115 cut, it must be remembered that the model is hung by its tip and the middle of its heel, and consequently the heel seat will be lowered relative to its axis of rotation by the magnification, while the toe tip will not. 120 The position of the reproduced bottom profile can therefore be determined by revolving the sole profile 44 around the toe tip 46 as center until the heel seat 48 has dropped to 1.1 the distance of the heel seat 50 from 125 the axis 52. This gives the sole profile 54 of the last to be cut as related to the axis 52, now considered as the axis of the block. The instantaneous center around which any section of the model must rotate at the instant 130

of its reproduction in order to produce the profile 54 is found as follows:—Consider the section at 56. We must determine a point *e* around which the section of the model at 56 may be rotated, all its radii taken from *e* being multiplied by 1.1, in the block and laid off from the center *a* around which the corresponding section 56 is rotating. The point *e* is determined by the necessity of 10 producing the point *b*, which is *eb* distant from the axis of rotation of the model, at the point *c* which is *ac* distant from the axis of rotation of the block. The grading ratio being 1.1, we must have

$$15 \quad \frac{ac}{eb} = 1.1 \quad (1)$$

The distance *ac* being known by the preliminary assumption as to the result to be 20 produced, the length *eb* is given by the above equation, and the point *e* therefore determined.

It is interesting to know what the form of the rest of the last will be. The point *f* 25 is likewise reproduced at *d*, where *d* is given by the relation

$$\frac{ad}{ef} = 1.1 \quad (2)$$

30 This gives the upper profile 57, of the last produced.

The locus of the points *e* is shown at 58. A line *g* drawn from the toe tip 46 through any point *e* will intersect the vertical at the 35 end of the heel in a point *h* which represents the required displacement of the heel dog 7 from the axis 52 for this instant of the reproduction. These displacements, computed through the mechanism of the lathe, 40 will give the shape of the cam 38, the general shape of which is shown in Fig. 6.

The shape of the locus 58 in Fig. 7 shows that the model returns to its normal axis of revolution during the cutting. This is the 45 reason for the preliminary assumption as to the position of the line 54. A cam could be formed according to the above method, which would reproduce the line 54 in coincidence with the line 44. Some distortion, 50 however, results from the tipping of the model around the point 46, and there will be, on the whole, more tipping of the model if 54 and 44 are to coincide. This distortion is due to the fact that when the model is 55 tipped by continually varying amounts, the sections reproduced are not all exactly parallel, whereas their reproductions in the block are parallel. The model sections are, however, substantially parallel since the maximum displacement of the heel dog will be 60 quite small.

This distortion can be avoided by moving both ends of the model simultaneously so as to keep it always "parallel to itself," and I 65 regard such procedure as within the scope of

my invention. This can be effected by the duplication of the elements 29, 28 etc. through 18, in connection with the toe dog 8, the pivot 30 being lengthened out to form a rockshaft. Such mechanism broadly is the 70 prior invention of another and is therefore not claimed herein. The cam shown in Fig. 5 is so designed as to hold the dog 7 in its normal position during the cutting of the 75 toe (38^a), to shift the dog during the cutting of the instep (38^b) and to hold it immovable during the cutting of the heel (38^c). This cam will bend down the shank and diminish the heel spring in the last cut. A perfectly straight cam as 38^a will cause the lathe to 80 cut in the ordinary way throughout the last.

It will be noticed that that portion of the locus 58 which extends from the point 46 to the portion *i*, at the ball, is nearly straight, that is, that the heel dog 7 remains 85 very close to *h* during all the cutting from the toe to the ball. A closely approximate result may therefore be produced by forming the cam 38 with its beginning portion straight, so as to hold the dog 7 fixed at *h* 90 until the ball is reached. The displacement of the point *h* may be computed very simply in accordance with the above formula (1). Expressed in words, the center of rotation of the model section at the ball must 95 be moved toward the sole of the model in order to raise the bottom of the ball just enough so that the width grading magnification will put it back in the same position in the block relative to the axis of the block 100 which it originally occupied in the model relative to the original or main axis of the model. In other words, the distance from the bottom of the ball to the main axis of the model must be divided by the width 105 grading ratio in order to obtain the position of the instantaneous axis of revolution for the ball section. The point *h* must then be so placed as to lift the point thus found into the axis of the lathe. The remainder of the 110 cam will then be designed as above explained in order to produce the outline desired from the ball to the heel.

The method explained above is perfectly 115 general. The outline 54 may be any outline whatever. All that is necessary is to determine the position of the outline in the lathe in the completed block, and then to determine the series of centers of rotation for the successive model sections in order to 120 produce it.

Another aspect of the phenomenon produced by the invention is the effective shifting of transverse laminæ of the model which are being traversed by the model wheel. 125 These are moved absolutely relatively to their normal position, and are also moved relatively to one another. In the machine shown, the rate of their relative shift, or the differential of their relative movement 130

throughout the series of the shifted lamineæ is entirely arbitrary, being predetermined in magnitude and direction at any instant by the design of the cam 38.

5 Still another aspect of the result accomplished by my invention is the generation, in the block, of pantographically reproduced sections of the model, differentially shifted upon one another, entirely irrespective of 10 the movement of the corresponding sections in the model which, in the machine shown, produces them, and I regard any method of producing this result, which is included by the appended claims, as within the scope of 15 my invention. To illustrate: A model might be sawed into lamineæ, the lamine might then be fastened together in relatively shifted position according to any profile whatever, and the reshaped model placed in the ordinary 20 lathe and copied according to the ordinary practice.

Indeed, many embodiments of my invention are possible. The shifting of the model which effects the desired modification of the 25 action of the width grader on the block may take the form of moving either end of the model in the proper direction, or of moving both ends of the model simultaneously in the same or in opposite directions, so that it may 30 tip more or less rapidly or may remain always parallel to itself, during the cutting. The effect desired may be also produced by shifting the block instead of the model, or by shifting both simultaneously. It is only 35 necessary that the similarity of their relations to the mechanisms that engage them (the model wheel and cutter) be varied during the cutting, and this may indeed be accomplished by shifting either one of the 40 four. I regard any such arrangement coming within the terms of my claims as within the scope of my invention.

My invention is not limited in its practice to lasts in which the magnification ratio is 45 different from unity. In case the width grader is set at zero, a last of the same width as the model but with different toe spring can be produced. I intend that the word "pantographic" shall be construed as including the magnification ratio of unity.

The word "variable" or terms similar to it, should not be understood as limited to the meaning "continuously variable." I intend that such terms shall imply merely 55 that the thing to which they are applied shall have different values at at least two different times or places, and that it may pass from one value to a different one continuously or discontinuously. The angles 60 in the cam 38 shown in Fig. 6 would produce discontinuous changes in the rate of shift, for example.

I intend that the words "last lathe" and words referring to its parts in the claims

shall be construed generically as referring 65 to the corresponding instrumentalities of machinery for reproducing plane or solid forms from models or patterns, including machines for producing patterns for articles of clothing, and pantographic reproducing 70 mechanism in general.

Having described the invention, what I claim as new and desire to secure by Letters Patent of the United States is:—

1. In a last lathe, means for rotating a 75 model and a block, and means for pantographically reproducing in the block sections of the model, and for shifting such reproduced sections upon one another as they are formed at a rate which may vary and is 80 arbitrarily predeterminable at any point during the cutting of the last.

2. In a last lathe, means for rotating a model and a block, and means for pantographically reproducing in the block sections of the model, and for shifting such reproduced sections upon one another as they are formed at a rate automatically variable 85 during the cutting of the last.

3. In a last lathe, means for rotating a 90 model and a block, and means for pantographically reproducing in the block sections of the model, and for shifting such reproduced sections upon one another as they are formed at a rate variable during the un- 95 interrupted cutting of the last.

4. In a last lathe, means for holding a model and a block, and means for pantographically reproducing in the block sections taken from the model in substantial 100 parallelism, and a cam and connections for shifting such reproduced sections upon one another as they are formed automatically at a rate which may vary and is arbitrarily predeterminable at any point of the model. 105

5. In a last lathe, means for holding a model and a block, and means for pantographically reproducing in the block sections taken from the model in substantial 110 parallelism, and for shifting such reproduced sections upon one another as they are formed at an automatically variable rate.

6. In a last lathe, means for holding a model and a block, and means for pantographically reproducing in the block sections taken from the model in substantial 115 parallelism, and a cam and connections for shifting such reproduced sections upon one another as they are formed with a variable acceleration.

7. In a last lathe, means for holding a model and a block, and means for pantographically reproducing in the block sections taken from the model in substantial 120 parallelism, and means for automatically 125 shifting such reproduced sections upon one another in order during their formation, at a variable rate.

8. In a last lathe, means for holding a model and a block, and means for pantographically reproducing in the block sections taken from the model in substantial parallelism, and for automatically shifting such reproduced sections upon one another in order during their formation at a controllable rate.

9. In a machine of the class described, means for relatively displacing sections of a model by arbitrarily varying amounts and means for pantographically reproducing such sections in the work.

10. In a machine of the class described, a cam and connections for differentially shifting sections of a model by arbitrarily varying amounts and means for pantographically reproducing such sections in the work.

11. In a machine of the class described, means for continuously shifting sections of a model upon one another in order at a rate which may vary and is predeterminable at any point in the model and means for pantographically reproducing such sections in the work.

12. In a machine of the class described, model controlling means for automatically relatively shifting sections of a model taken in order, upon one another at a rate which may vary and is predeterminable at any point of the model, and means for pantographically reproducing such sections in a block.

13. In a machine of the class described, means for relatively shifting sections of a model taken in order by predeterminedly variable amounts and means for pantographically reproducing such sections in a block.

14. In a machine of the class described, connections between the model and the main drive for automatically continuously shifting sections of a model upon one another in order at a variable acceleration, and means for pantographically reproducing such sections in a block.

15. In a machine of the class described, an irregular control mechanism for automatically relatively shifting sections of a model taken in order by predeterminedly variable amounts and means for pantographically reproducing such sections in a block.

16. In a machine of the class described, means for automatically relatively shifting sections of a model taken in order at a rate independently and simultaneously predeterminable for all points of the model and for pantographically reproducing such sections in a block.

17. In a last lathe, guiding and cutting instrumentalities, model holding mechanism and block holding mechanism, constructed and arranged to present a model and a block to these instrumentalities respectively in similar relations, and means for varying the

similarity of these relations at a rate independently and simultaneously predeterminable at all points during the cutting of a last.

18. In a last lathe, guiding and cutting instrumentalities, model holding mechanism and block holding mechanism comprising dogs, constructed and arranged to present a model and a block to these instrumentalities respectively in similar relations, and a dog shifting means for varying the similarity of these relations at an acceleration variable automatically during the cutting of a last.

19. In a last lathe, guiding and cutting instrumentalities, model holding mechanism and block holding mechanism, constructed and arranged to present a model and a block to these instrumentalities respectively in similar relations, and means for varying the similarity of these relations at a rate independently predeterminable at all points during the uninterrupted cutting of a last.

20. In a last lathe, guiding and cutting instrumentalities, mechanism for rotating and presenting a model and block to said instrumentalities respectively and means for varying at a rate variable during the cutting of a last the relation of one of said objects to its rotational axis.

21. In a last lathe, guiding and cutting instrumentalities, mechanism for rotating and presenting a model and block to said instrumentalities respectively and a cam and connections for varying at a rate automatically variable during the cutting of a last the relation of one of said objects to its rotational axis.

22. In a last lathe, guiding and cutting instrumentalities, mechanism for rotating and presenting a model and block to said instrumentalities respectively and means for compounding motion with the motion engendered by said mechanism for automatically varying at a rate non-uniform during the cutting of a last the relation of one of said objects to its rotational axis.

23. In a last lathe, a model wheel, a cutter, mechanism for presenting a model and block to said wheel and cutter respectively, and rotating them about longitudinal axes, and means for effecting simultaneous angular displacement of said model or said block about an axis substantially perpendicular to said longitudinal axis and parallel to the tread face at a speed which may vary and is predeterminable at all points during the turning of a last.

24. In a last lathe, a model wheel, a cutter, mechanism for presenting a model and block to said wheel and cutter respectively, and rotating them about longitudinal axes, and a cam and connections for automatically effecting simultaneous angular displacement of said model or said block about an axis substantially perpendicular to said longitudinal axis.

tudinal axis and parallel to the tread face at a speed variable during the turning of a last.

25. In a last lathe, a model wheel, a cutter, mechanism for presenting a model and block to said wheel and cutter respectively, and rotating them about longitudinal axes, and a holding means for moving said model or block, in a direction perpendicular to its bottom during the turning, at a rate variable during a part of the turning of a last.

26. In a last lathe, a model wheel, a cutter, a swing frame having centers for supporting and rotating a model and a block in operating relation to said wheel and cutter, one of said centers comprising a dog constructed and arranged to be movable relatively to the axis of rotation of said center at a rate variable during the cutting 20 of a last.

27. In a last lathe, a model wheel, a cutter, a swing frame having centers for supporting and rotating a model and a block in operating relation to said wheel and cutters, one of said centers comprising a dog constructed and arranged to be movable relatively to the axis of rotation of said center at a rate automatically variable during the cutting of a last.

28. In a last lathe, model wheel and cutter carriages, centers for supporting and rotating a model and a block, a dog movably mounted on one of said centers and connections between one of said carriages and said dog for moving said dog relatively to the axis of said center at a rate which may vary and is predeterminable at any point during the cutting of a last.

29. In a last lathe, model wheel and cutter carriages, centers for supporting and rotating a model and a block, a dog movably mounted on one of said centers and connections between one of said carriages and said dog for moving said dog relatively to the axis of said center at a rate automatically variable during the cutting of a last.

30. In a last lathe, model wheel and cutter carriages, centers for supporting and rotating a model and a block, a dog movably mounted on one of said centers and connections between one of said carriages and said dog comprising a member adjustably mounted on the carriage for moving said dog relatively to the axis of said center during the cutting of a last.

31. In a last lathe, model wheel and cutter carriages, centers for supporting and rotating a model and a block, a dog movably mounted on one of said centers and connections between one of said carriages and said dog comprising a cam for moving said dog relatively to the axis of said center during the cutting of a last.

32. In a last lathe, model wheel and cutter carriages, centers for supporting and ro-

tating a model and a block, a dog movably mounted on one of said centers and connections between one of said carriages and said dog comprising a cam adjustably mounted on said carriage for moving said dog relatively to the axis of said center during the cutting of a last.

33. In a last lathe, model wheel and cutter carriages, centers for supporting and rotating a model and a block, a dog movably mounted on one of said centers and cam operated means for moving said dog relatively to the axis of said center during the cutting of a last.

34. In a last lathe, a model wheel carriage, a cutter carriage, a swing frame having centers for suspending and rotating a model and a block, a dog movably mounted on one of said centers, a cam on one of said carriages, and a member mounted on the main frame of the lathe, engaging said cam and connected with said dog.

35. In a last lathe, a model wheel carriage, a cutter carriage, a swing frame having centers for suspending and rotating a model and a block, a dog movably mounted on one of said centers, a cam on one of said carriages, and a member mounted on the main frame of the lathe, engaging said cam and connected with said dog, said connection comprising a chain of mechanism having a joint substantially in the pivotal axis of the swing frame.

36. In a last lathe, a model wheel and cutter, model and block rotating instrumentalities comprising a dog automatically movable both toward and away from its axis of rotation during the cutting of a last to alter the normal relation of progressively reproduced sections of the last.

37. In a last lathe, a model wheel and cutter, model and block rotating instrumentalities comprising a dog automatically movable both toward and away from its axis of rotation during the cutting of a last at a rate variable from point to point along the last during the cutting.

38. In a last lathe, a model wheel and cutter, model and block rotating instrumentalities comprising a dog automatically movable both toward and away from its axis of rotation during the cutting of a last at a rate which may vary and can be predetermined at any point during the cutting.

39. In a last lathe, a model wheel and cutter, model and block rotating instrumentalities comprising a dog automatically movable relatively to its axis of rotation in one direction and later in the opposite direction, during the cutting of a last, at arbitrary automatically controlled rates to alter the normal relation of progressively reproduced sections of the last.

40. In a last lathe, a model wheel and cutter, model and block rotating instrumen-

talities comprising a dog automatically movable relatively to its axis of rotation in one direction and later in the opposite direction during the cutting of a last at independent 5 rates to alter the normal relation of progressively reproduced sections of the last.

41. That improvement in the art of manufacturing lasts which consists in producing in a block pantographic reproductions of 10 successive sections of a model shifted upon one another at a rate arbitrarily variable through the series of those shifted.

42. That improvement in the art of manufacturing lasts which consists in producing 15 in a block pantographic reproductions of successive substantially parallel sections of a model, the reproductions being shifted upon one another at a rate automatically variable throughout the series.

20 43. That improvement in the art of manufacturing lasts which consists in producing in a block pantographic reproductions of successive sections of a model and shifting them upon one another at a rate automatically 25 variable throughout the series, the directions of shift before and behind the ball being opposed.

44. That improvement in the art of manufacturing lasts which consists in producing 30 in a block pantographic reproductions of substantially parallel sections of a model in succession, and raising those in one portion of the last thus formed by arbitrarily varying amounts.

35 45. That improvement in the art of manufacturing lasts which consists in relatively shifting sections of a model in any desired manner and in reproducing them while so relatively shifted, in a block.

40 46. That improvement in the art of manufacturing lasts which consists in producing in a block pantographic reproductions of successive sections of a model and shifting them upon one another continuously and 45 automatically during the last cutting, the directions of shift before and behind the ball being opposed.

47. That improvement in the art of manufacturing lasts which consists in making 50 pantographic reproductions of substantially parallel sections of a model and arranging them in order along an arbitrary profile.

48. In a machine of the class described, means for holding a model and a block, and 55 means for pantographically reproducing substantially parallel sections of the model and for placing them in order upon an arbitrary profile.

49. In a machine of the class described, 60 means which continuously shifts sections of a model upon one another in order at a variable rate, and means for pantographically reproducing such sections in a block.

50. In a machine of the class described, 65 means capable of continuously shifting sec-

tions of a model upon one another in order at a variable rate, and means for pantographically reproducing such sections in a block.

51. That improvement in the art of manufacturing lasts which consists in presenting a block to a cutter and a model to a guide, governing the relation between the cutter and block by that between the model and guide to reproduce the model section by section, and causing variations in the relations between the four objects independent of the reproductional relative movements to effect an arbitrary relative shift between reproduced sections parallel to the sections. 70 75 80

52. In a machine of the class described, model and block holding instrumentalities, model and block following instrumentalities, means for causing relative movement between the block and its following instrumentalities to effect a pantographic reproduction of the model, section by section, and a cam and connections for combining with such movement a movement effecting an arbitrary relative shift between the reproduced sections. 85 90 95

53. In a pattern copying machine, a grading mechanism for magnifying or reducing differential elements of the model in relation to a grading axis, and means for shifting the model transverse to the grading axis to relatively displace reproduced elements according to an arbitrary predetermined law. 100

54. In a pattern copying machine, a grading mechanism for magnifying or reducing differential elements of the model in relation to a grading axis, and a cam and connections for relatively shifting the model and work in relation to the said axis. 105

55. In a pattern copying machine, a grading mechanism for magnifying or reducing differential elements of the model in relation to a grading axis, and a cam longitudinally related to the said axis for shifting 110 the model transverse to the axis.

56. In a pattern copying machine, a grading mechanism for magnifying or reducing differential elements of the model in relation to a grading axis, and a cam longitudinally related to the said axis for effecting a relative shift of the model and work transverse to said axis. 115

57. In a pattern copying machine, means for holding a model and a work piece, and means for systematically reproducing in the work sections of the model and shifting any desired portion of such reproduced sections relatively to one another at an arbitrarily variable rate as they are formed. 120 125

58. In a pattern copying machine, means for holding a model and a work piece, and a grading mechanism and connections for pantographically reproducing in the work sections taken from the model and for auto- 130

matically shifting such reproduced sections relatively to one another at an arbitrarily variable rate as they are formed.

59. In a pattern copying machine, means 5 for holding a model and a work piece, and means for systematically reproducing in the work piece sections taken from the model and for shifting such reproduced sections relatively to one another as they are formed, 10 at a rate which may vary and is arbitrarily predeterminable at every point of the work.

60. That improvement in the art of pattern copying which consists in producing in a work piece systematic reproductions of 15 substantially parallel sections of the model differentially and non-geometrically shifted relatively to one another at a rate which may vary and is arbitrarily predeterminable at all points of the work.

20 61. That improvement in the art of copy turning which consists in automatically reproducing in a work piece pantographic reproductions of successive substantially parallel sections of a model and shifting them 25 relatively to one another differentially, the rate of shift varying arbitrarily in different parts of the work.

62. That improvement in the art of manufacturing solid bodies which consists in presenting a block to a cutter and a model to 30 a guide, governing the relation between the cutter and block by that between the model and guide to reproduce the model section by section, and causing variations in the relations between the four objects independent 35 of the reproductional relative movements to effect a relative shift between reproduced sections at a rate which is arbitrarily predeterminable at all points of the work.

40 63. In a three-dimensional pattern copying machine, model and block holding instrumentalities, model and block following instrumentalities, means for causing relative movement between the block and its 45 following instrumentalities to effect a pantographic reproduction of the model, section by section, and connections for combining with such movement a movement effecting a relative shift between the reproduced sections at a rate which is arbitrarily predeterminable at all points of the work.

64. In a three-dimensional pattern copying machine, a model holder, a model wheel, a block holder and a cutter, the relation between 55 the block holder and cutter being pantographically controlled by the relation between the model holder and model wheel; and means for effecting a relative movement between a said controlled and a said controlling element to effect relative shifting between differential elements in the reproduction, at a rate which is arbitrarily predeterminable at all points of the work.

65. In a three-dimensional pattern copy- 65 ing machine, a model holder, a model wheel,

a block holder and a cutter, the relation between the block holder and cutter being pantographically controlled by the relation between the model holder and model wheel; and a driving mechanism for effecting a 70 relative movement between a said controlled and a said controlling element to effect relative shifting between differential elements in the reproduction at a rate which is arbitrarily predeterminable at all points of the 75 work.

66. In a three-dimensional pattern copying machine, a model holder, a model wheel, a block holder and a cutter, the relation between the block holder and cutter being pantographically controlled by the relation between the model holder and model wheel; and driving mechanism for causing a movement of one of the said elements independent 80 of its behavior incident to the pantographic reproduction, at a rate which is arbitrarily predeterminable at all points of the work.

67. In a machine of the class described, a model holder, a model wheel, a block holder and a cutter, the relation between the 90 block holder and cutter being controlled by the relation between the model holder and model wheel; supporting and operating mechanism for relatively moving said elements to effect pantographic reproduction, 95 and a driving mechanism intermediate between one of said elements and the supporting and operating mechanism to effect relative shifting between differential elements in the reproduction, at a rate which is arbitrarily predeterminable at all points of the 100 work.

68. In a machine of the class described, a model holder, a model wheel, a block holder and a cutter, the relation between the block 105 holder and cutter being pantographically controlled by the relation between the model holder and model wheel, supporting and operating mechanism for relatively moving said elements to effect reproduction of differential elements and a mobile connection intermediate between one of said elements and the supporting and operating mechanism to effect relative shifting between differential elements in the reproduction, at a rate which 110 is arbitrarily predeterminable at all points of the work.

69. In a machine of the class described, a model holder, a model wheel, a work holder and a work contacting tool, supporting and 120 operating means for these four instrumentalities constructed and arranged to cause relative systematic reproductional movement between the model instrumentalities and the work instrumentalities respectively, the relation between the work instrumentalities being governed primarily by the relation between the model instrumentalities to produce systematic reproduction of differential elements of the model in the work, and driving mecha- 125 nism for causing a movement of one of the 130

nism for compounding with the normal reproduction action of a said instrumentality a movement to effect a shifting between reproduced differential elements in the work 5 at a rate which is arbitrarily predeterminable at all points of the work.

70. That improvement in the art of producing solid objects having a systematic resemblance to a solid pattern which consists 10 in controlling the relation between the work and a work contacting tool by the relation between a model and a model guide to repro-

duce differential elements of the model according to a pantographic law, and effecting a movement of one of the said elements independent of its action incidental to pantographic reproduction to effect relative shifting of reproduced differential model elements, at a rate which is arbitrarily predeterminable at all points of the work. 15

In testimony whereof I have signed my name to this specification. 20

EDWIN J. PRINDLE.
